CAPPING MACHINERY

Howard E. Gantzer, Kenmore, N. Y., assignor to
Consolidated Packaging Machinery Corporation,
Buffalo, N. Y., a corporation of New York

Application August 3, 1933, Serial No. 683,432

16 Claims. (Cl. 226—88)

This invention relates to a mechanism for assembling caps and containers having cooperating threaded surfaces whereby the cap is screwed onto the container, particularly adapted for assembling caps having linings or packings for engaging the mouth of the container and forming a tight closure therewith.

My invention more particularly relates to a novel capping chuck adapted to be used in connection 10 with the type of machine described in United States Patent No. 1,773,960, issued August 26, 1930, to R. N. Cundall, to which reference is made for a more complete description of the machine.

Chucks as heretofore developed and specifically 15 illustrated in the above patent have a number of objectionable features, especially in applying caps having enamelled or highly finished surfaces. One object of my invention is to devise a chuck which will handle such caps and apply the necessary pressure to secure the cap onto the container without marking or marring its surface.

The ordinary cap is formed of thin metal 20 pressed into shape and having a screw thread formed therein by rolling its flange between forming dies. Such a cap is never uniform and it is desirable to locate it with respect to the container by seating its upper end and top firmly within a chuck, this portion of the cap being more uniform than the remainder thereof. One object 25 of my invention is to devise a chuck which will function in this manner.

Another object of my invention is to devise a chuck which will apply the cap with a great deal of downward pressure to compress the neck of 30 the container into the cap lining without distorting the shape of the cap.

Another object of my invention is to device a chuck which will screw a cap onto a container to the desired extent and will not tend to rotate the 35 cap beyond the point which has been adjustably determined as its limit of safety.

The principle involved in my chuck is that of applying pressure to the top and sides of a cap through certain members actuated by springs, 40 rather than by outside positive mechanical means, thus forming a cap holder which is completely self-contained so that one may be simply removed from the spindle and replaced by another of different dimensions or adapted to operate on a 45 different type of cap. I have herewith illustrated several possible modifications in which certain functions are performed by one member while in others the functions may be performed by modifications of this member, but in all cases it will

be noted that the fundamental principles as outlined above apply.

This device incorporates certain essential features necessary or desirable to facilitate the operation of securing caps to containers by mechanical means, and comprises a chuck which is self-contained and is operated by the reciprocation of the chuck itself as it approaches and recedes from the container.

Other and further advantages and features of 10 my invention will be pointed out in the following specification taken in connection with the drawings wherein like numerals refer to like parts, and will be particularly pointed out in the claims.

Referring to the drawings:

Figure 1 is a section taken through the type of 15 machine illustrated in United States Patent No. 1,773,960, and having my improved chucks attached thereto,

Figure 2 is a section taken through one form of 20 my chuck,

Figure 3 is a section taken through this form of 25 chuck along the line 3—3 of Figure 2,

Figure 4 is a section taken along the line 4—4 of Figure 2,

Figure 5 is an exploded view in perspective of 30 this form of chuck,

Figure 6 is a view partly in section of a chuck 35 illustrating certain modifications which may be made,

Figure 7 is a view partly in section of another 40 form of chuck,

Figure 8 is a sectional view illustrating the 45 chuck applying a cap to a container,

Figure 9 is a sectional view of my chuck in 50 opened position, and

Figure 10 is a bottom view thereof.

Referring to Fig. 1, a brief description of the machine will now be given which will be sufficient to set forth the mode of operation of my 40 invention. The numeral 10 refers to an upright, stationary post which extends through a bearing 11 mounted on table 12 which rotates about post 10. Table 12 carries gripping jaws 13 which are adapted to grip the container 14 and carry it with 45 the table while preventing it from rotating. The movable jaws of grippers 13 are operated by rocker shafts 15 journaled at their upper ends in a rotary supporting head or disc 16 and carrying rocker arms 17 and follower rollers 18 above head 16. 50 The rollers 18 follow a cam slot 19 in a stationary cam plate 20 through which post 10 extends. As the head 16 rotates, rollers 18 approach and recede from shaft 15, thus rocking the shafts 15 and causing the movable jaws of grippers 13 to clamp 55

and release containers placed on table 12 between the jaws.

The containers may be placed on the table, in position to be grasped by the grippers, and removed therefrom by any suitable means. Caps are also fed in upright position to the machine by suitable means and are gripped by the chucks at the proper time in the sequence of operations.

Cam plate 20 is mounted on the lower surface 10 of a supporting plate 21 fixed to post 10 by a set screw 22. Plate 21 carries an upwardly extending ring 23 having its upper edge cut away at suitable points to form a cam of the desired contour. The outer edge of plate 21 terminates in 15 a flange having gear teeth 24 thereon. Plate 16 has bearings 25 therein in which are mounted upwardly extending spindles 26 whose upper ends are carried in bearings 27 in a plate 28 mounted to rotate about post 10. Extending radially inward from each spindle 26 is a follower roller 30 which rides on the cam surface of ring 23. Spindles 26 have pinions 31 thereon whose teeth mesh with gear teeth 24, so that as plates 16 and 28, and the other parts comprising what may be 25 termed a chuck turret, rotate about post 10, the spindles will be rotated while rising and falling in accordance with cam 23. The rollers 30 normally follow the surface of cam 23, but at the position in which a cap is being applied to a 30 container cam 23 is cut lower than the rollers can ordinarily follow and they are yieldingly constrained downward by a holding cam 32 pivotally mounted on plate 21 and pressed downward by spring 33. A greater or lesser yielding pressure may be applied downwardly upon the top 35 of a cap as the compression of spring 33 is adjusted by bolt 34 about which it is mounted, or by altering the shape of cam 32.

Spindles 26 carry the chucks, indicated generally at 40, at their lower ends and have mounted therein chuck rods or plungers 35 yieldingly constrained upward by springs 36. Mounted on plate 28 is a ring 37 carrying adjustable abutments 38 above and in line with the enlarged 45 heads of plungers 35. As a spindle 26 is raised by cam 23 the enclosed plunger 35 is limited in its upward movement by abutment 38 and opens the jaws of the chuck as will be hereinafter explained.

For a more detailed operation of this mechanism, reference is again made to United States Patent No. 1,773,960, wherein the means to cause the chuck in its open position to descend upon a previously positioned cap, and carry it up above the normal height of a container is shown. With this cap so grasped the chuck continues to rotate about its own axis and also about the post 10 while a container is positioned on table 12 and grasped by grippers 13. The follower 30 now 55 rides downwardly along the lower portion of cam 23, shown in Fig. 1, and the chuck rotates and partially screws the cap onto a container.

The holding cam 32 does not extend for a greater distance than necessary to firmly apply the cap to the container, and chuck 40 will again be raised by cam 23 and the jaws thereof opened ready to receive another cap while the capped container is ejected from the machine.

One form of chuck is detailed in Figs. 2 to 50 inclusive and will now be described. The chuck is fastened to the end of spindle 26 by suitable means such as screw threads on the upper end of member 45 which forms part of a universal joint connecting the chuck jaws to the driving spindle. Member 45 comprises two downwardly

extending arms 46 terminating in a ring 47. A portion of the outer surface of each arm 46 is cut inwardly above ring 47 to form a reduced portion at 48. Two diametrically opposed pins 49 extend downwardly from ring 47. Ring 47 bears against a ring 50 in which are four slots 51 spaced equally around its inner circumference and extending radially outward toward its outer circumference. The inner and outer diameters of rings 47 and 50 are respectively equal. Ring 50 is seated on a ring 52 having substantially the same outer diameter but whose inner diameter is materially reduced. Two pins 53 extend upwardly from ring 52. Pins 49 fit into two of the slots 51 and pins 53 fit into the others, thus forming a positive driving connection between spindle 26 and ring 52 while allowing the ring 52 and the remainder of the chuck to float or have a universal movement in a horizontal plane in order to accommodate variations which are to be found in the ordinary type of container. Ring 52 is seated upon a friction disc 54 composed of fiber, leather, cork or other material, which is in turn seated within a holding cavity in the chuck body 55 and frictionally tends to rotate the chuck. Rings 47, 50 and 52 and friction disc 54 fit within this holding cavity and a retaining ring 56 is slipped over the arms 46 and fastened to chuck body 55 by means of screws 57, the inner diameter of the holding ring being smaller than the ring 47 but larger than the reduced portion 48 on arms 46 so as to allow universal movement of the chuck. A nose ring 58 is affixed to chuck body 55 and extends downwardly therefrom, forming a cavity within which the chuck jaws 59 are placed. The chuck jaws have inwardly disposed pivot pins 60 which are seated on a flange 61 on the lower end of a jaw stem 62, whose upper end extends through block 55 and ring 52. A spring 63 encircles jaw stem 62 and is adjustably compressed against the top of ring 52 by means of nuts 64. The chuck jaws 59 have rounded flanges 65 thereon which bear against the inner surface of the nose ring 58 and keep the upper ends of the jaws seated while allowing the lower ends to pivot outwardly in order to be opened sufficiently to grasp a cap therein. Extending inwardly from each chuck jaw is a flange 66 whose upper surface is bevelled downwardly and against which bears the correspondingly bevelled lower end of a stripper pin 67 which extends coaxially upward into jaw stem 62. The lower surfaces of flanges 66 form a seat against which the top of a cap bears. A pin 68 extends outwardly from jaw stem 62 and into the space between two of the pivot pins 60 to unite the chuck jaws and jaw stem for rotary movement. Two of the chuck jaws are cut away on adjacent edges as at 69 and a pin 69 on nose ring 58 extends into the slot so formed and unites the chuck jaws to the nose ring for rotation therewith. The inner, lower end of nose ring 58 is bevelled at 70 and flanges 71 on the chuck jaws bear against this bevelled surface. Chuck rod 35 extends downwardly through a bore 72 in the member 45 and into a bore 73 in jaw stem 62, the latter bore having a larger diameter than the rod in order to allow free movement of the chuck, and bears against the upper end of stripper pin 67.

The spindle 26 rotates disc 52 through the universal connection and tends to rotate the nose ring and chuck jaws through the friction disc 54, the torque required to prevent the jaws from rotating being regulated by the compression of spring 63. This compression is normally such

that the chuck will apply a cap to a container until the lining therein is lightly seated on the mouth of the container, whereupon the spindle and member 45 will continue to rotate while the 5 chuck jaws remain stationary.

The operation of the chuck from the time it is opened to receive a cap until it again reaches the same stage will now be described. The jaws when opened are pivoted outwardly about flanges 10 65, the stripper 67 having pushed them down, and the pivot pins 69 having pulled jaw stem 62 downwardly against the force of spring 63 which tends to close the jaws. Flanges 71 fitting over the end of nose ring 58 tend to retain the chuck 15 jaws in open position. As the chuck rotates about post 10 it is lowered onto a previously positioned cap until the lower end of stripper pin 67 contacts therewith and is forced upward, allowing the chuck jaws 59 to pivot inwardly until 20 flanges 71 bear against the bevelled surface 70, whereupon the jaws will snap shut due to the compression of spring 63. The chuck is now raised while a container is gripped by grippers 13. Thereafter follower 30 rides down on the 25 lower portion of cam 23 while the chuck screws the cap onto the container until the lining is lightly seated thereon. The chuck now slips and remains stationary until follower 30 is forced downwardly by the holding cam 32. Flanges 66 30 of the chuck jaws, bearing down on the top of the cap, compress the lining into the neck of the container and relieve the highly frictional contact of the screw threads of the container and cap. The chuck now rotates until it again slips, 35 thus firmly seating the cap where it will retain the lining compressed into the container neck to tightly seal the container. In this way the cap is assembled on the container without undue rotative force being required, the effort necessary 40 to compress the lining being transmitted downwardly upon the top of the cap while the rotative force is applied only when the cap is substantially free from frictional contact with the container.

45 The container is held firmly by the grippers 13 while at the same time the chuck has a grip on the cap, so that as follower 30 is again raised by cam 23 the jaws of the chuck are usually caused to snap open. However, it sometimes 50 happens that the supply of containers is temporarily exhausted through accident or carelessness, or that the container feeding means becomes temporarily out of order, so that a container is not present to receive the cap. The 55 same situations may arise in the cap feeding means, so that a cap is not present to be attached to a container, or it may happen that the container or cap is defective so that they do not unite. In any of the above situations it is important that the chuck jaws be opened, or a more or less serious jam and delay will occur. An important feature of my invention is that the 60 chuck is positively opened at each upward movement of the spindle. This is accomplished by 65 rod 35 striking abutment 38 as cam 23 raises the chuck, the rod forcing stripper pin 67 downwardly and the bevelled surfaces of the pin and chuck jaws cooperating to open the chuck jaws.

This feature is doubly important in another 70 respect. As mentioned above, the cap or container may be defective and a tight closure cannot be effected. In machines heretofore used the defect could not be discovered easily and a poorly capped container would be allowed to go out to 75 the consumer. With my chuck, when a defective

closure occurs the cap will be stripped from the container and then ejected from the chuck. The open container will be ejected from the machine, but the operator can instantly detect it and cause it to be discarded. In this manner it is assured 5 that defective containers are prevented from leaving the factory.

The vertical face 74 on the stripper pin cooperates with vertical faces 75 on the chuck jaws to hold them open, while a skirt 76 on the stripper 10 pin prevents it from falling out. (Figs. 9 and 10.) The stripper pin thus locks the jaws open until it is forced upwardly by contact with the top of a cap. The lower faces of the chuck jaws may be bevelled inwardly as at 77 in order that the 15 inner edges of the chuck jaws will not project so far downwardly when the jaws are open as to strike the top of the cap before it is positioned within the chuck. The inner surfaces of the jaws may be ribbed or knurled, or smooth, depending 20 upon the type of cap being used. Some caps have a bead extending around their tops and for this reason the chuck jaws may be relieved as at 78. It has also been found to be best in some situations that a second relieved portion as at 79, (Fig. 25 6) extend around the chuck jaws at the position where the thread of the cap would normally contact therewith, and that the lower edge of the chuck be bevelled off as at 80, in order to allow a better contact of the chuck jaws with the cap 30 and to prevent the thread from tilting the cap.

Cam 32 and spring 33 have several functions to perform. The cam lowers the cap on the container and the adjustable compression of spring 33 determines the extent to which the lining is 35 compressed by such lowering. In addition it is apparent that increased pressure on cam 32 will increase the gripping action of jaws 59 due to the cooperation of the bevelled surface 70 and flanges 71. The more that spring 33 is tightened, the 40 greater will be the downward pressure on the top of the cap and the greater the peripheral gripping action. The downward pressure on the top of the cap is important and necessary to seat the lip of the container in the liner of the cap, thereby 45 insuring a more perfect seal, and the increase in gripping action is important and necessary to overcome the increased frictional contact of the lining and the lip of the container. Prior to this point in the operation of the machine the gripping action has been brought about by the action 50 of spring 63 alone, which is not sufficient to overcome the aforementioned frictional contact. As a correlative of the foregoing it is apparent that greater force will be applied to the friction washer 54 to cause the chuck jaws to rotate with the spindle. The functions of spring 33 as outlined above are extremely important in that a uniform 55 adjustment of all the chucks is affected without stopping the machine. If it were not for this feature the machine would have to be stopped and each set of nuts 64 adjusted to correct any deviation from the correct closing operation. As a result it would require great care and a large loss of time to effect uniform adjustment of all of the 60 chucks. With the present structure the chucks are individually adjusted before the machine is started, and collectively adjusted to meet instant 65 requirements as the machine is in operation.

Fig. 6 illustrates a modification wherein the 70 chuck body and nose ring are combined in one integral piece 85 and other parts are modified correspondingly to adapt the chuck to caps of very small diameter while retaining the exact principles of the previously described chuck. The 75

member by means of which the chuck is united to the spindle may completely enclose the jaw stem as indicated, the purpose of having separated arms such as 46 in Fig. 5 being merely to allow access to the adjusting nuts 64. It is also apparent from this figure that the capping machine may be adjusted to operate on various sizes of caps, simply by removing ring 56 and replacing the chuck jaws and nose ring and associated parts with others of the size desired, or by replacing the entire chuck.

Fig. 7 is a further modification adapted to operate on large caps. In this modification the nose ring 86 is screwed onto a member 87 having a seating cavity within which the jaw stem spring is retained. Member 87 has an outwardly extending flange which fits over and bears down upon a ring 88 attached to a member 93 and which is disposed above a ring 89 having a smaller outer diameter. Ring 89 is seated on a ring 90 which bears against friction disc 91 seated on a shoulder of nose ring 86. Pins 92 extend upward from the outer edge of ring 90 and pass through holes in ring 88 into bores in member 93 which carries the attaching means 94. Seated in these bores are springs 95 adjustably compressed by set screws 96, and comprising additional spring means acting on the friction washer to more evenly distribute the downward pressure thereon. The space between member 87 and member 93 is larger than the enclosed rings so that a universal movement of the chuck jaws is allowed. Ring 90 is positively rotated by the spindle and tends to rotate the chuck through the friction disc 91, the torque transmitted being varied by adjustment of screws 96. The remainder of the chuck is identical with the chuck shown in Fig. 2, except for the difference in size allowed by this form.

Fig. 8 illustrates my chuck applying a cap 99 to a container 14 and illustrates how the chuck jaw flanges press down upon the top of the cap, compressing the lining 101 and relieving the friction between the cooperating threads at 100.

Figs. 9 and 10 clearly show the chuck ready to receive a cap. The cooperation of stripper pin 67, chuck jaws 59 and nose ring 58 is clearly expressed in these views, as well as illustrating the extent to which the jaws are opened.

It is now apparent that I have invented a cap assembling chuck which is efficient in its operation and embodies desirable features which are not to be found in others previously used.

As will be evident to those skilled in the art, my invention permits of various modifications and I do not intend to be limited to the specific details illustrated, the scope of my invention being set forth in the appended claims which are to be broadly construed.

What I claim is:

1. In a container capping machine, a rotary cap applying chuck comprising a rotatable body, cap engaging jaws associated therewith, friction means transmitting torque from said body to said jaws, and spring means to control the torque transmitted to said jaws, said spring means also acting to close said jaws.

2. In a container capping machine, a rotary cap applying chuck comprising a rotatable body, cap engaging jaws associated therewith, said jaws having pivot pins thereon, a member substantially enclosing said jaws, a jaw stem extending through said member, said stem having a flange at its lower end upon which said pivot pins

bear, and a spring encircling said jaw stem and yieldingly retaining said jaws in said member.

3. In a container capping machine, a rotary cap applying chuck comprising a rotatable body, cap engaging jaws associated therewith, said jaws having pivot pins thereon, a member substantially enclosing said jaws, a jaw stem extending through said member, said stem having a flange at its lower end upon which said pivot pins bear, a spring encircling said jaw stem and yieldingly retaining said jaws in said member, and a stripper pin coaxially within said stem and resting on said jaws.

4. In a container capping machine, a rotary chuck having pivoted jaws therein, spring means to close said jaws, and a stripper pin to open said jaws, said pin and said jaws having vertical faces thereon which register when the jaws are open and lock the jaws in open position against the compression of said spring.

5. In a rotary cap applying chuck, pivoted cap engaging jaws, each of said jaws having a flange thereon bearing against the top of the cap and a vertical face engaging the side of the cap, said vertical face having a groove substantially parallel with and intermediate its top and bottom edges.

6. In a container capping machine a rotary chuck having gripping jaws therein, a friction means to transmit driving torque to said jaws, a spring adjustable to vary the gripping action of said jaws while varying the torque transmitted, and external means adjustable to vary said gripping action and torque independently of said spring.

7. In a container capping machine a plurality of rotary chucks mounted on a turret, each of said chucks having cap gripping jaws, frictional torque transmitting means and means adjustable to vary the gripping action of said jaws and the torque transmitted, and means to collectively adjust the gripping action and torque transmitted independently of said first means.

8. In a container capping machine, a plurality of rotary chucks, each having gripping jaws and means to vary the gripping action of said jaws, and means to collectively adjust the gripping action independently of said first means.

9. In combination; a cap applying chuck normally acting under the pressure applied by gravity alone comprising a member and cap engaging jaws substantially enclosed therein, means to cause said jaws to engage the flange of a cap to grip the same, and means to vary the pressure on said chuck, said member and said jaws having wedging engagement whereby variations in pressure applied to the chuck during its cap applying action cause variations in the gripping pressure of said jaws.

10. In a container capping machine, a chuck comprising a member and gripping jaws substantially enclosed within said member, a jaw stem supporting said jaws and extending beyond said member, a spring cooperating with said jaw stem to draw said jaws within said member to thereby close said jaws in gripping a cap, and cooperating flanges on said member and said jaws whereby the jaws may be locked in opened position against the tension of said spring.

11. A cap applying chuck comprising a member and gripping jaws substantially enclosed within said member, a jaw stem supporting said jaws and extending beyond said member, a spring cooperating with said jaw stem to draw said jaws

within said member, flanges on said jaws, and a cooperating bevelled face on said member whereby said jaws are caused to converge during movement of said jaws into said member.

5 12. A cap applying chuck comprising a member and gripping jaws substantially enclosed within said member, a jaw stem supporting said jaws and extending beyond said member, a spring cooperating with said jaw stem to draw said jaws

10 within said member to grip a cap, a stripper pin coaxial with said jaw stem, cooperating faces on said jaws and said stripper pin whereby relative movement of said stripper pin causes spreading of said jaws against the force of said spring, and

15 cooperating faces on said member, said jaws and said stripper pin whereby said jaws are locked in extended open position until said stripper pin is retracted.

13. A cap applying chuck comprising a member 20 and gripping jaws substantially enclosed within said member, a jaw stem supporting said jaws and extending beyond said member, a spring cooperating with said jaw stem to draw said jaws within said member to grip a cap, a stripper pin

25 coaxial with said jaw stem, cooperating bevelled faces on said jaws and said stripper pin whereby relative movement of said stripper pin causes extension and spreading of said jaws against the force of said spring, cooperating faces on said

30 member, said jaws and said stripper pin whereby said jaws are locked in extended open position until said stripper pin is retracted, and cooperating faces on said member and said jaws acting to

35 wedge said jaws into converging cap gripping relation upon retraction of said stripper pin.

14. A rotary cap applying chuck for use in a container capping machine comprising, a rotatable body, cap engaging jaws associated therewith, a member substantially enclosing said jaws

and comprising a rigid backing for said jaws in opened and closed position, friction means transmitting torque from said body to said jaws, and a joint connecting said body to said member comprising relatively movable driven and driving elements allowing lateral play of said jaws relative to said body.

5 15. A rotary cap applying chuck for use in a container capping machine comprising, a rotatable body, cap engaging jaws associated therewith, a member substantially enclosing said jaws and comprising a rigid backing for said jaws in opened and closed position, friction means transmitting torque from said body to said jaws and

10 spring means associated therewith to control the torque transmitted to said jaws, other spring means associated with said jaws acting to close said jaws, and a joint between said body and said member comprising relatively movable driven and driving elements allowing lateral play of said 20 jaws relative to said body.

16. In a screw capping machine, a cupped shaped chuck adapted to receive snugly a cylindrically skirted cap therein, wherein the chuck includes a vertically disposed movable member

25 having a flange at its lower end, a plurality of closely adjacent arcuate sections forming the side wall of the chuck and each having inwardly extending means at its upper end resting upon said flange, a cam ring surrounding the sections and within which said vertically disposed member and said sections are mounted for limited axial movement with respect thereto, said cam ring and sections having cooperating portions to contract the sections in clamping a cap and for 30 locating the sections concentrically therewith when the vertically disposed member is moved axially with respect to the ring.

35 HOWARD E. GANTZER.
